UNITED STATES PATENT OFFICE

92,094

DESIGN FOR A TEXTILE FABRIC

Werner R. Kaufmann, East Elmhurst, Long Island, N. Y., assignor to Yale Fabrics Corporation, New York, N. Y., a corporation of New York

Application March 28, 1934, Serial No. 51,203

Term of patent 3½ years

To all whom it may concern:

Be it known that I, WERNER R. KAUFMANN, a citizen of United States, residing at the town of East Elmhurst, L. I., in the county of Queens and State of New York, have invented a new, original, and ornamental Design for a Textile Fabric, of which the following is a specification, reference being had to the accompanying drawing, forming part thereof.

The figure is a plan view of a textile fabric, showing my new design. The design as shown is one including a selvage. This selvage is shown at the bottom of the drawing.

I claim:

The ornamental design for a textile fabric, substantially as shown and described.

WERNER R. KAUFMANN.
